CONTROL DEVICE

Newton C. Schellenger, Elkhart, Ind., assignor
 to Chicago Telephone Supply Co., Elkhart,
 Ind., a corporation of Indiana

Application December 26, 1933, Serial No. 703,917

6 Claims. (Cl. 200—154)

This invention relates to control devices and particularly to a switch adapted to be combined with a variable resistance device to form a combination unit adapted for use as volume control or tone control apparatus in electrical sound transmitting systems such as radio sets, public address systems, and the like.

More particularly, the invention relates to the switch portion of a combination unit including a variable resistance device having a resistance element and a contactor engaging the resistance element and movable thereover for varying the resistance of the circuit in which the variable resistance is connected and an improved switch of the slow break type arranged to be opened and closed by a predetermined movement of the contactor.

In control devices of the aforementioned type, particularly where the devices are to be employed in radio receivers, it is especially desirable that the switch be small, inexpensive to construct, certain in operation, capable of carrying relatively high currents, operable with a minimum of arcing, and without chattering, both when moved into closed position and when jarred or vibrated while in closed position. These numerous and exacting requirements arise from the compact design of radio receivers and severe usage to which they are subjected.

The switch, when employed as a power current switch, must be capable of carrying for a short time, a short-circuit current of many times the normal current, and, when employed for example in an automobile radio receiver must be capable of carrying for a short time substantially the short circuit current of the storage battery which may amount to several hundred amperes. Also, when employed in a portable receiver, the switch must be constructed so as to maintain good contact and operate satisfactorily even when subjected to jars and vibrations.

Where a switch is to be employed to control a circuit supplied with 60 cycle alternating current, such as is commonly employed to supply the power for operating radio receivers, I have found that a switch of the "slow break" type, wherein the contacts are separated relatively slowly, is to be preferred over a switch of the "quick-break" type, wherein the contacts are separated relatively quickly. In the latter type of switch, although the contacts are separated quickly, they are not separated quickly enough to prevent the drawing of a long, destructive arc between the contacts. This hot arc will continue in existence until the voltage decreases to zero to quench

the arc, hence, unless the arc is struck at a point of time on the voltage cycle only a very short period before the voltage value decreases to zero, the arc will be in existence sufficiently long to cause detrimental burning due to its comparatively great average length and corresponding large amount of heat developed.

Since the arc is sustained through a relatively great proportion of the half-cycle, the arc is drawn to a relatively great length due to the rapid separation of the contacts, and a substantial amount of heat is generated with the consequent burning and pitting of the contacts and the emanation of conductive gases and incandescent particles of metal, all of which effects are detrimental to the life of the switch.

The present invention contemplates the design of a switch of the slow break type wherein the contacts are separated so slowly that, substantially irrespective of the portion of the voltage cycle at which separation of the contacts is initiated, the contacts are not separated a sufficient distance to produce an arc which generates any considerable amount of heat, before the voltage decreases to a zero value to quench the arc; thereafter the contacts are separated, as will be seen, with no arc, the separation being sufficient to prevent re-striking of the arc before the voltage value again increases from zero to maximum. Since the arc is quenched prior to attaining any substantial length, no substantial amount of heat is generated and there is no appreciable burning of the contacts and substantially none of the destructive effects usually attendant upon the occurrence of an arc of long occurrence.

In a manually operated switch, and particularly in a switch of the type arranged to be operated by the movement of the contactor of a variable resistance device through a portion of its travel beyond that portion of its travel wherein it is active to vary the effective resistance of the device, it is desirable that the completion of the opening or closing be signalled by a tactile and/or audible signal. An example of such a signal is the click accompanying the operation of the well-known "snap" switch. However, the snap switch is a quick break switch and, as pointed out in the foregoing, is not as satisfactory for many installations as a slow break switch.

The present invention provides a switch of the slow break type wherein the contacts are maintained in contact under a sufficient pressure to prevent chattering caused by jars or vibrations; wherein the contacts are separated without de-

structive arcing; wherein the contacts are brought together with a wiping blow and are separated with a wiping action to keep the surfaces clean and polished; and wherein the completion of the opening or closing of the switch is indicated by a positive signal.

One of the objects of the present invention is the provision of the switch portion of a combination variable resistance device and switch unit which is simple in construction, inexpensive to manufacture and efficient in operation.

Another object of the invention is the provision of the switch portion of a combined variable resistance device and switch unit of the type wherein the switch is operated by the movement of the contactor of the variable resistance device through a predetermined portion of its travel, in which unit the operation of the switch is accompanied by the minimum amount and intensity of arcing.

Another object of the invention is the provision in switch unit of the aforementioned type of a novel mechanism for transmitting movement from a variable resistance device to the switch contacts.

Another object of the invention is the provision in a switch of the slow break type of an arrangement for producing a tactile and audible indication of the completion of the opening or closing of the switch.

Another object of the invention is the provision in a switch or a combined switch and variable resistance device unit of a housing arrangement wherein the terminal elements of the switch are completely surrounded and protected by the housing arrangement.

Other objects of the invention will appear from the following description taken in connection with the appended drawings, wherein:

Fig. 1 is a top plan view showing a combination variable resistance device and switch constructed according to the invention;

Fig. 2 is a side elevational view, showing the device shown in Fig. 1, with portions of the housing broken away to show the interior;

Fig. 3 is a bottom plan view showing that portion of the variable resistance device which carries the switch, with the switch secured thereto;

Figs. 4, 5, and 6 are bottom plan views, showing the switch, with a portion of the actuator cut away to show the construction, the switch being shown in "closed", "break" and "open" positions, respectively;

Fig. 7 is an end elevational view showing the switch;

Figs. 8, 9, 10, and 11 are fragmentary sectional views showing constructional details of the switch and associated actuator;

Fig. 12 is an enlarged isometric view of the actuator;

Fig. 13 is an isometric view of the blank from which one of the contacts is formed;

Figs. 14 and 15 are bottom plan and end elevational views, respectively, of the terminal housing member;

Figs. 16 and 17 are bottom plan views showing a modified form of switch, the switch being shown in "closed", and "open" positions, respectively;

Figs. 18 and 19 are fragmentary bottom plan and longitudinal sectional views showing a portion of a switch having a modified construction of circuit completing member;

Figs. 20 and 21 are views similar to Figs. 2 and

3 showing a device having a modified form of actuator and switch;

Figs. 22, 23, and 24 are bottom plan views showing the switch of Fig. 20 and a portion of the actuating element, the switch being shown in "closed", "dead center" and "open" positions, respectively;

Figs. 25 and 26 are fragmentary sectional views showing constructional details of the switch of Fig. 20;

Fig. 27 is an isometric view showing the blank from which the contact member is formed;

Fig. 28 is an isometric view showing a modified form of the gear portion of the actuator of Fig. 21; and

Fig. 29 is a reduced plan view showing the grounding connector.

Referring more in detail to the drawings, Fig. 1 shows a combined switch and variable resistance device unit, the variable resistance embodying constructional features disclosed and claimed in my copending applications Serial No. 672,955, filed May 26, 1933, and Serial No. 671,031, filed May 15, 1933.

The variable resistance device 1 comprises a base 2 of insulating material carrying a flat carbonaceous resistance element 3, formed by depositing a conducting film on an insulating support, and connected at its ends to terminals 4, 5, secured to the base 2 and a threaded bushing 6 in which bushing 6 is journaled an operating shaft 7. On the operating shaft 7 is mounted an actuator arm 8 which carries an upstanding switch actuating pin 9 and a contact arm 10, the free end of which arm 10 engages a disk-shaped contact element 11 resting upon the resistance element 3. The contact arm 10 is electrically connected to a third terminal 12, whereby, upon rotation of the shaft 7, the contact element 11 is moved over the surface of the resistance element 3 to vary respectively the amount of resistance connected between each of the end terminals 4, 5 and the central terminal 12. As will be understood, if the variable resistance device is to be employed as a simple variable resistance, instead of a voltage divider, connections will be made only to one end terminal and the center terminal.

A metallic cupped housing member 13 is provided with integral ears 14, 15, 16, 17 which are bent over against the base 2 to secure the housing member 13 thereto, thus constituting a closed housing for the variable resistance device 1.

A switch 18 is housed in a housing member 19 (Figs. 4 to 6) of molded insulating material and having a recess 20 in which is disposed a pair of contact members 21, 22 and the switch actuating or cam portion 23 of an actuator 24.

The contact member 21, which is of general straight shape, and formed from a resilient metal having good electrical and thermal conductivity, such as phosphor-bronze alloy, has an end seated in a slot 25 in an end wall 26 of the housing member 19. The contact member is firmly positioned by the corner of a boss 27 extending from the end wall and an opposing projection 28, extending from a side wall 29 of the housing member 19 which corner and projection 28 grip the end of the contact member 21 and by the cam 23 and the end of the other contact member 22. The contact member 21 is formed with an inclined portion 30 providing a hump 31, and with a contact portion 32 bent to make an angle of substantially 135° with the principal portion of the contact member 21.

The second contact member 22 is similarly seated in a slot 33 and gripped at the end by the other corner of the boss 27, a projection 34 and the cam 23, and is held thereby in substantial parallelism with the first contact member 21. The second contact member 22 is likewise formed with an inclined portion 35 and hump 36 and, in addition, has a portion 37 extending substantially perpendicularly from the principal portion 10 toward the contact portion 32 of the other contact member 21, which contact portion 32 is engaged under pressure, when the switch is in closed position, by a contact portion 38 formed by bending out the end of the perpendicularly extending portion 37.

The corners of the boss 27 and the projections 28, 34 are so positioned relatively to their respective contact members 21, 22 that the portions of the contact members 21, 22 which extend into 20 the housing 19 are forced toward one another. When the switch is in closed position, the contact portions 32, 38 engage under pressure which action, combined with the positioning of the ends of the contact members 21, 22 by the boss 27 and 25 the projections 28, 34, causes the contact members 21, 22 to be firmly gripped in the housing 19. When the switch is in a position, such as shown in Figs. 5 or 6, wherein the contact members 21, 22 do not have full pressure engagement, the cam 23 serves to position the ends of 30 the contact members 21, 22 to thus assist the boss 27 and projections 28, 34 in gripping the contact members 21, 22.

The contact member 21 is formed from a blank 35 similar to that shown in Fig. 13, which blank, as will be seen, has a portion 39 formed with a perforation 40 for connection to a conductor (as will hereinafter be described) and an open transverse slot 41 and a tapered portion 42 extending 40 therefrom.

Referring to Fig. 11, the connection portion 39 of the contact member 21 extends through the slot 25 in the end wall 26 of the housing member 19 and the transversely slotted portion engages 45 the slotted portion of the end wall 26 to secure the contact member 21 against longitudinal movement. The tapered portion 42 extends longitudinally of the housing 19 and is spaced therefrom by virtue of its tapered form, thereby being 50 movable freely within the housing 20 without rubbing against the wall thereof. The other contact member 22 is formed from a blank similar to, but longer than, the blank 42 and has a portion 43 provided with a perforation 44 and a slot 55 (not shown), the slot engaging the slotted portion of the end wall 26 of the housing member 19; the tapered portion of this contact is also free from engagement with the walls of the housing member 19.

60 Rotatably mounted in the housing member in a position between the contact members 21, 22 is the actuator 24, formed of molded insulating material. The actuator 24 has the shape shown in detail in Fig. 12 and comprises the switch actuating portion 23 formed as a cam, lying in the switch housing 19 (Fig. 4) and positioned to engage the contact members 21, 22, and a gear portion 47 (Fig. 2), constituting the female gear element of an intermittent gear mechanism, which 65 gear portion 47 lies in the variable resistance device housing 13 in the path of movement of the switch actuating pin 9 which pin 9 constitutes the male element of the intermittent motion mechanism.

70 75 As shown in Figs. 8, 9, 10, and 12, the actuator

24 is formed with a pair of trunnions 48, 49 projecting from its ends, one of which trunnions 48 is journaled in an integral cup 50 formed in the bottom of the wall of the switch housing member 19, the trunnion 49 being journaled in a collar 51 formed in a tongue 52 struck from and offset from the end wall of the cupped housing member 13.

The cam portion 23 of the actuator 24 (Figs. 4 to 6) has two diametrically opposite toes 53, 54 positioned for cooperation with the contact members 21, 22 respectively. The toe 53 does not engage its cooperating contact member 21 when the switch is in the closed position (Fig. 4), but the other toe 54 is arranged to bear against its contact member, in all positions of the switch, with sufficient force to prevent the actuator 24 from rattling in its bearings.

A stop element 55 formed integral with the housing member serves to halt the actuator 24 when the cam portion 23 lies angularly of the transverse axis of the housing member 19, in the position shown in Fig. 4. The stop element 55 also halts the actuator 24 when the latter is in the "open" position, shown in Fig. 6, wherein the cam portion 23 lies substantially transversely of the housing 19 and the toes 53, 54 are in engagement with their corresponding contact members 21, 22 and contact elements 32, 38 are spread out of mutual engagement.

When the switch 18 is in the closed position, the contact portion 32 bears against the contact portion 38. The contact portions 32, 38 are pressed into engagement by the boss 27 and projections 28, 34, against the inherent spring pressure of the contact members 21, 22 and the latter are so shaped and positioned that the force of each is applied along a line directed approximately at an angle of 45° to the line of application of the force exerted by the other contact member, whereby the pressure of one contact element against the other is much greater than the force exerted to move either contact element in the direction in which the cam moves it. This wedging of the contact elements provides a contact pressure sufficiently high that engagement of the contact elements is positive, the contact resistance is uniform, and the contact elements are so tightly pressed together that the vibrating of the switch mounting as will often occur in service, cannot cause chattering of the contact elements with the consequent arcing and burning of the contact elements.

When the switch is in closed position, the perpendicular portion 37 of the contact member 22 is sprung at a greater than normal angle by engagement with the other contact member 21. As the cam 23 is rotated about its pivot in a counter-clockwise direction (as viewed in Figs. 4 to 6) the toe 54 presses out upon the contact member 22 to move the principal portion thereof away from the other contact member 21. As the rotation of the cam 23 is continued, the other toe 53 engages its cooperating contact member 21 and the contact members 21, 22 are spread apart. During the movement of the actuating member 24 and the simultaneous movement of both contact members 21, 22, the spring tension of the contact member 22 acts to move the perpendicular portion 37 in a direction to decrease the angle which the perpendicular portion 37 makes with the principal portion of the contact member 22. This action, combined with the separating movement of the contact members 21, 22, causes the contact portion 38 to be drawn

along the surface of the other contact portion 32 to provide an extensive wiping action therebetween as will be seen by comparing the position of the contact portions 32, 38 shown in Fig. 4, with their position in Fig. 5. In Fig. 4 the contact elements 32, 38 are in closed position and in Fig. 5, they are at the end of the wiping movement and in the "break" position, just prior to the separating movement. The extent of the wiping action is augmented by the movement of the contact portion 32 outwardly along a line lying at a small angle to the plane of the areas of contact of the contact elements 32, 38.

Upon further rotation of the cam 23, the contact members 21, 22 are still further spread and the contact portions 32, 38 separated and moved to the position shown in Fig. 6. As will be seen from Fig. 5, the last points of engagement are the heel portion of the contact portion 32 and the toe of the other contact portion 38 and hence any arcing which takes place occurs between these portions of the contact elements and not between the areas that are in contact when the switch is in the fully closed position.

The contact members 21, 22 are formed with the inclined portions 30, 35 positioned for engagement by the toes 53, 54 when the arm 8 is in the "open" position, shown in Fig. 6, wherein the contact members 21, 22 are held out of engagement by the cam 23. The inclined portions 30, 35 provide the angular humps 31, 36 on the contact members 21, 22 whereby, when the switch is being thrown into the "open" position and the toes 53, 54 ride over these humps 31, 36 and onto the inclined portions 30, 35 the turning movement of the actuator 24 is accelerated by the spring action of the contact members 21, 22 in squeezing against the toes 53, 54, as the latter tend to ride down the inclined portions 30, 35. The acceleration is made positive at its beginning by the positioning of the humps 31, 36 for engagement by the toes 53, 54 simultaneously whereby a "dead center" position is attained by the actuator 24 when the humps 31, 36 are engaged by the toes 53, 54. As the cam 23 passes through the dead center position, the squeezing action of the contact members 21, 22 upon the cam 23 rapidly rotates the cam 23 into a position transverse of the housing 18 (Fig. 6) wherein it lies up against the stop 55 and is held in position by the pressure of the contact members 21, 22 to maintain the contact members 21, 22 apart. On account of the lost motion in the intermittent gear mechanism, the cam moves into the open position freely and quickly after it passes the dead center position.

If, when the switch is in open position, as shown in Fig. 6, the cam 23 is rotated in a clockwise direction, the toes 53, 54 ride up on the inclined portions 30, 35, against a resistance to rotation of the cam offered by the necessity of the cam 23 spreading the contact members 21, 22 as it rides up the inclined surface. As the toes 53, 54 ride over the humps 31, 36, the cam passes through the "dead center" position and thereafter, the resistance to rotation is suddenly released and the contacts spring rapidly into engagement. Because of the lost motion connection provided by the intermittent gear mechanism, the cam 23 is free to rotate independently of the movement of the pin 9 and hence the cam 23 is rotated to closed position very rapidly.

The action of the contact members 21, 22 in closing is similar to, but the reverse of, the

action in opening. Since the contact members 21, 22 are under considerable stress when spread apart, the release of the spreading force, causes the contact members 21, 22 to return to the closed position rapidly and with considerable force, the contact portions 32, 38 being moved into engagement with a sharp blow.

When the contact portions 32, 38 first meet, they are in the positions shown in Fig. 5, and the perpendicular portion is under substantially no stress, but due to the wedging action of the contact members 21, 22, as they move into the position shown in Fig. 6, the perpendicular portion 31 is bent at a greater than normal angle thus causing the contact portions 32, 38 to be slid along one another into the positions shown in Fig. 6. This sliding or wiping action is in addition to and accompanies the sharp blow resulting from the rapid engagement of the contact portions 32, 38.

It will be seen that, upon the closing of the switch, the contact elements are brought into engagement with considerable force and, as they engage, the surfaces slide along each other through a distance approximately equal to the length of the area of contact. This combined blow and wiping action serves to thoroughly loosen and dislodge any loose foreign matter such as particles of burned contact material, scale, oxide, dirt, and the like, and the wiping action serves to brush such loosened material off the surfaces and to polish the latter.

The wedging action between the contact members prevents bouncing when the contact elements are brought into contact and, when the switch is in closed position, prevents separation of the contact elements due to jars or vibrations, hence no burning or welding of the contact elements can take place due to these causes. Such burning and welding is of very common occurrence in many switches and is highly destructive and it is of greatest importance to insure against such harmful effects as the consequent roughening of the contact surface accelerates these effects. The life of the switch is very materially reduced unless some provision, such as for example in the present invention, is made to prevent these harmful effects.

The gear portion of the actuator 24, which extends into the variable resistance device housing 13, has a cut out portion or slot 56 forming two teeth 57, 58 and movably positioned to receive the switch actuating pin 9 when the arm 8 of the variable resistance device is in its initial position with the contactor 11 near one of the end terminals 4 or 5. When the arm 8 is in its initial position, the switch 18 is in the open position. As the arm 8 is moved from the initial position, by the rotation of the shaft 7, the pin 9 moves in the slot 56 to engage the tooth 57 to rotate the actuator 24 which closes the switch 18 as described above. Upon continued movement of the arm 8, the pin 9 disengages from the slot 56 of the actuator 24 leaving the switch 18 in closed position. When the arm 8 is moved back toward the initial position, the pin 9 re-engages the actuator 24 and, as the arm moves into the initial position, bears against the tooth 58 to rotate the actuator 24 and open the switch 18.

During the first portion of the movement of the actuator 24 to open the switch 18, the toes 53, 54 (Figs. 4 to 6) ride on the contact members 21, 22 against an increasing resistance to rotation offered by the spring action thereof. When the toes 53, 54 ride over the humps 31, 36, this resist-

ance to rotation is suddenly released and the rotation of the actuator 24 is assisted instead of being resisted as previously. Because of the intermittent gear connection between the variable resistance and the switch, the gear portion 47 is free to disengage from the pin 9 which it does under the influence of the squeezing action of the contact elements 21, 22 upon the cam 23. Thus, if the shaft 7 is being manually rotated to rotate the actuator 8 which moves the pin 9, a positive indication in the nature of a jerk is felt by the operator as the "dead center" position is passed through and thus a tactile indication of the operation of the switch is provided. Such an indication is provided in an analogous manner by the inclined portions 30, 35 and humps 31, 36 to signal the closing of the switch. As stated above, the movement of the actuator 24 in either direction of rotation is halted by the stop element 55. This stop element 55 is positioned to halt the actuator 24 prior to the normal end of the accelerated movement induced by the spring action of the contact members 21, 22. Thus, the actuator 24 strikes the stop element 55 with considerable force and an audible click is produced which click serves as an audible indication that the operation of the switch has been completed. Thus it will be understood that the signal provided to indicate the completion of the operation of the switch is both tactile and audible.

The switch housing member 19 has a pair of depending bosses or lugs 59, 60 which project through perforations 61, 62 in the variable resistance device housing member 13 to locate the switch housing 19 thereon. Struck up from the housing member 13 are two integral ears 63, 64 which are bent over respectively against two integral inset steps 65, 66 formed on two sides of the housing member 19 and sloped upwardly away from the housing member 19 to secure the latter firmly on the variable resistance device housing 13. The steps 65, 66 are indented from the side of the housing member 19 to provide notches 67, 68 which provide additional locking of the housing 19 as well as additional strength of the portions 65 and 66. Interposed between the switch housing 19 and the variable resistance device housing 13 is a flat disk-shaped insulating member 69 having perforations (not shown) receiving the actuator 24, the ears 63, 64, the lugs 60, 61, respectively, which insulating member 69 serves to insulate the contact members 21, 22 from the variable resistance device housing 13.

When the switch housing 19 is held against the insulating member 69 by the bent over ears 63, 64, the contact members 21, 22 are clamped at their end portions 39, 43 between the bottom wall of the switch housing 19 and the insulating member 69 thus positively positioning the contact members 21, 22 and preventing movement thereof in the slots 25, 33. The tapered portions do not engage either the housing 19 or the insulating member 69 and hence are free to move as above described.

The straight, perforated end portion 39 of the contact member 21 is projected from the switch housing member 19 to constitute a terminal element for an insulated conductor 70 constituting a portion of the circuit (not shown) in which the switch 18 is to be connected. The bare end of the conducting portion 71 of the conductor 70 is projected through the perforation 40 in the end portion 39 and bent over against the latter, and a quantity of solder 72 locks the conducting por-

tion 71 and the end portion 39 together and provides positive electrical connection therebetween. A second insulated conductor 73 having a bare end 74 is similarly connected to the end portion 43 of the other contact member 22 constituting a second terminal element by solder 75. The insulating member 69 serves to insulate the bare ends 71, 74 and solder 72, 75 from the variable resistance device housing member 13.

Seated on the variable resistance device housing member 13 and in abutment with the switch housing member 19 is a terminal housing member 76 which, with the variable resistance device housing member 13 and the switch housing member 19, constitutes a housing for the terminal elements and the bare ends 71, 74 of the conductors 70, 73; the corners of the side walls of the housing 76 are formed with notches 77, 78 (Figs. 14 and 15) to accommodate the conductors 70, 73. Formed integrally with the terminal housing member 76 is a central partition 79 having a tongue 80 which enters a recess 81 (Figs. 7 and 8) formed in the end of the switch housing member 19 and a pair of bosses 82, 83 which extend through perforations (not shown) in the variable resistance device housing member 13 and the insulator 69. An ear 84 struck up from the variable resistance device housing member 13 through the insulating plate 69 and bent over against an inclined flange or inset step 85 cooperates with the tongue 80 and the bosses 82, 83 to lock the terminal housing member 76 securely against the variable resistance housing member 13 and the switch housing member 19. This terminal housing member may, of course, be omitted if desired.

In Figs. 16 and 17 is shown a switch embodying certain of the inventive principles hereinbefore set forth but having the contact members shaped and arranged to provide a simultaneous double break in the circuit. Such an arrangement is often desirable in that the break is more positive than in a single break switch and arcing consequently even less than the slight arcing which takes place in the previously described switch. Such a switch may, in certain cases, be made more compact than the form described above.

In this modified form, the switch 86 comprises a recessed housing member 87 formed in general similarly to the housing of the first form of switch and a pair of generally parallel contact members 88, 89 formed like the contact member 21 of the first form and seated in slots 90, 91, a boss 92 and projections 93, 94 holding the contact members 88, 89 in the housing 87 and tensioning them toward each other in a manner similar to that described in connection with the switch of Figs. 4-6. The contact members 88, 89 are provided with inclined portions 95, 96 and humps 97, 98 and the ends are oppositely bent at angles of approximately 135° relative to their respective body portions to form contact portions 99, 100 which, when the switch is in closed position, have pressure engagement respectively with contact elements 101, 102 constituted by bent ends of a circuit-completing member 103.

The circuit-completing member 103 is triply bent to form two diverging return bends 104, 105 which bends are seated in suitably shaped open arcuate seats 106, 107 and are held therein by a stud 109 upstanding from the floor of the housing 87; the stud 109 bears against the circuit-completing member 103 intermediate the return bends 104, 105. The circuit-completing member 75

103 is so formed that it is securely held in its seats 106, 107 and against the stud 109 by its own inherent spring pressure, it having been compressed when inserted and then permitted to 5 expand to its normal position, thus causing the intermediate portion and the ends of the return bends 104, 105 to press against the cooperating portions of the housing 87.

The contact portions 99, 100 of the contact members 88, 89 are so positioned that normally they would be closer together than the contact portions 101, 102 of the circuit-completing member 103 when the latter are in their free positions (as seen in Fig. 17). Thus, when the switch 15 86 is in the closed position shown in Fig. 16, the contact members 88, 89 force the ends of the circuit-completing member 103 closer together, thereby providing a relatively high pressure between the contact portions 99, 100, 101, 102.

20 The return bends 104, 105 are free to move in their respective seats 106, 107 under the pressure exerted by the contact members 88, 89 and hence the free ends of the circuit-completing member 103 have a considerable unrestrained 25 length and the contact portions 101, 102 are movable through a considerable distance under the influence of the contact portions 99, 100. Such long movement of the contact portions 101, 102 provides a very substantial wiping action between 30 the contact portions 99, 100, 101, 102 as the contact members 88, 89 are moved into or out of engagement with the circuit-completing member 103.

35 As the free ends of the circuit-completing member 103 extend at considerable angles to the free ends of the contact members 88, 89 respectively, the cooperation between these members is analogous to that explained in connection with the first form of switch. The members being 40 mutually approachable at considerable angles, there is a very substantial wedging action therebetween which provides a high contact pressure between the contact elements and in addition, there is a substantial travel of the contact 45 portions relative to and in contact with one another which insures a satisfactory wiping of the contact surfaces.

Where it is desired to construct the switch 86 (Figs. 16 and 17) as a three pole switch, the circuit-completing member is formed as shown in Figs. 18 and 19. In this switch 86a, which is similar to the switch 86 shown in Figs. 16 and 17, except as hereinafter pointed out, a casing 111 has a pair of contact members 112, 113 provided 55 with contact portions 114, 115 cooperating with contact portions 116, 117 formed in the free ends, a circuit-completing member 118 having return bends 119, 120 seated in recesses 121, 122 in the housing 111. Formed integrally with the 60 central portion of the circuit-completing member 118 and bent at a right angle thereto is a tongue 123 which extends through an open slot 124 in the end wall of the casing 111 and projects therefrom to constitute a terminal having a perforation 125 for receiving a circuit conductor (not shown). When the switch housing 124 is clamped in place the tongue 123 is firmly held between the wall of the switch housing and the insulating plate.

70 In Figs. 20 to 27 is shown another embodiment of the invention, the inventive concept being applied to a switch of the double pole type, a variant form of actuator being shown for connecting the switch with the variable resistance device.

The variable resistance device 126 is similar to that shown in Fig. 1 and comprises a base 127, a cupped housing member 128 secured thereto, a threaded mounting bushing 129 secured in the base 127 and journaling a shaft 130 on which 5 shaft is mounted an actuator arm 131 carrying a switch actuating pin 132 positioned to move into engagement with an actuator 133.

The actuator 133 comprises a metallic gear 134 pivotally mounted on the inside of the housing member 128 by a hollow rivet 135 and has a pair of spaced downwardly offset teeth 136, 137 positioned to cooperate with the actuating pin 132 to constitute an intermittent gear mechanism, and a pair of opposed yokes 138, 139 having open 15 slots 140, 141. The open slots 140, 141 receive depending legs 142, 143 of a cam portion 144 of the actuator 133 which has a trunnion 145 journaled in an integral bearing 146 in the inside of the wall of a switch housing member 147 and 20 another trunnion (not shown) journaled in the hollow rivet 135. The switch housing member 147 is secured to the variable resistance device housing 128 in a manner analogous to that previously described, as will appear from the drawings. 25

The side edges 148, 149 of the cam portion 144 of the actuator 133 cooperate respectively with contact members 150, 151 secured in the switch housing 147. The movement of the cam 144 is halted by the legs 142, 143 striking against the 30 ends of arcuate slots 152, 153 in the housing member 128 hence no stop element need be provided in the switch housing 147 as is required where the previously described actuator 24 is employed.

The switch housing member 147 is shown in Figs. 20-22 and comprises a molded insulating member having a recess 154 formed with a pair of open arcuate extensions 155, 156 providing spaced seats. Nested in the extension 155 is the contact member 150 having a return bend 157 40 shaped to fit the seat. The contact member 150 is formed from a blank similar to that shown in Fig. 27, the material being resilient and having good electrical and thermal conductivity such as phosphor-bronze alloy. The blank comprises an 45 enlarged connection portion 158 having a perforation 159 and an open slot 160 therein and a reduced tail 161 having a pair of ears 162, 163 extending from the edge at points on both sides of the portion in which the return bend 157 is 50 made.

The contact member 150 has its return bend 157 loosely seated in the recess 155, as stated above, and has the slotted connection portion 158 projecting through a slot 164 in the end wall 165 opposite the end wall in which the recesses 155, 156 are formed. The connection portion 158 is locked between the housing member 147 and an insulating plate 166 (Fig. 25) interposed between the switch housing 147 and the variable resistance 60 device housing 128. The ears 162, 163 near the return bend serve to space the edges of the reduced portion from the insulator 166. The step portion 167 on which the return bend rests spaces the spring from the switch casing to prevent 65 portions of the spring that have greater movement from rubbing on the floor of the housing 147. The ears 162, 163 do not bear tightly enough against the insulator 166 to prevent movement of the return bend as a whole.

The other contact member 151 is formed in an identical manner and is seated in the seat 156 and held by a slot 168 in a position corresponding to, but opposite the position of the first contact member 150.

Projecting through a slot 169 formed in the end wall intermediate the first slots 164, 168, is a short contact member 170, having a connection portion formed similarly to those of the long contact members 150, 151 and a short portion 171 wedged between a boss 165a, a projection 172 on the end wall and a stud 173 upstanding from the bottom wall of the housing 147, the short portion 171 terminating slightly beyond the stud 173 in a bent end 174 constituting a contact portion.

The free end of the corresponding long contact member 150 has a bent end 175 constituting a contact portion positioned, when the switch is in the position shown in Fig. 22, to press with considerable force against the contact portion 174 formed on the short contact member 170.

A slot 176 similar to the slot 169 receives a second short contact member 177 and a suitably disposed projection 178 and the stud 173 secure the short contact member 177 in a manner corresponding to that in which the other contact element 170 is secured, a contact element 179 on this member cooperating with a contact element 180 of the associated long contact member 151.

The long contact members 150, 151 are so formed and disposed that the contact portions 175, 180 are movable in arcs in directions such that when the contact portions 175, 180 are moved into engagement with their corresponding contact elements 174, 179 there is a wedging engagement therebetween and considerable contact pressure is developed. The contact portions 175, 180 are spread more than normally when they engage their corresponding contact portions 174, 179 in the position of Fig. 22 so that, in this position, the return bends are under initial compression.

When the actuator 133 is swung to rotate the cam portion 144, the edges 148, 149 bear against parallel portions of the long contact members 150, 151 to release the pressure which the contact portions 175, 180 exert upon their corresponding contact portions 174, 179 and during the initial portion of this movement the contact portions 175, 180 are pushed across the other contact portions 174, 179 respectively to provide a substantial wiping action therebetween.

As the edges 148, 149 of the cam portion 144 ride onto inclined portions 181, 182 formed by bends in the long contact members 150, 151 respectively, the cam portion 144 passes through a position (Fig. 23) which is, in effect, a dead center position and thereafter, the movement of the actuator 133 is accelerated by the squeezing action exerted on the cam portion 144, the cam portion 144 being rapidly moved, without being under the control of the switch actuating pin 132, to a position wherein the legs 142, 143 of the cam portion 144 strike against the ends 152, 153 of the arcuate slots.

The gear portion of the actuator may be formed in an alternative manner as shown in Fig. 28 by punching a flat gear 183 from a sheet of insulating material which gear 183 has the general shape of the metallic gear portion 134 shown in Figs. 20, 21 and 25 with a cut out 184 cut therein to provide gear teeth 185, 186 for engagement by a switch actuating pin (similar to pin 132) and a pair of yoke portions 187, 188 adapted to receive the legs of a cam portion (similar to cam 144).

Where it is desired to electro-magnetically and electrostatically shield the variable resistance device, as explained more in detail and claimed in connection with a snap switch and variable resistance device in my copending application Serial No. 675,377, filed June 12, 1933, an electrical

grounding connection for the housing 13 is provided by a thin connector 13a. The connector 13a surrounds the shaft and is clamped at one end by the securing washer 6a, which locks the bushing in the housing. The other end of the connector 13a is clinched by the ear 14 thus electrically connecting the housing 13 to the bushing and through the bushing to the shaft which latter may be grounded. A similar connector 128a is shown in Fig. 20 in connection with the housing 10 128.

It will be seen from the foregoing that the switch in all forms shown and described above provides for a "slow break", that is, the contact elements are separated relatively slowly. This switch is distinguishable from the well-known "snap" switch since in the present switch, the separating movement of the contact elements is under the control of the operator until after the circuit is broken whereas in the "snap" switch the operator has no direct control over the movement of the contact elements, the separating movement being initiated only after the snapping mechanism has been energized and released and the operator has lost control over the operation of the switch.

It will further be seen that the invention is not to be limited to the employment of the switch with a variable resistance device but it may be employed with any other device having an actuating member for transient engagement with the gear portion of the actuator, or the switch may be employed by itself and operated directly by providing an actuating mechanism adapted to transiently engage the actuator to rotate the latter.

I claim:

1. A switch comprising, a base, a plurality of spring contact members, means mounting said members on said base for mutual engagement, means including a cam rotatable into engagement with at least one of said contact members for controlling the movement of said contact members into and out of engagement, means for accelerating the movement of said cam and stop means for halting the movement of said cam, said accelerating means including an inclined surface on at least one of said contact members and the stop being positioned for engagement by said cam during the engagement of said cam with said inclined surface.

2. A slow break switch comprising a plurality of contact elements, means for moving said contact elements apart including a cam engaging at least one of said elements, transiently engageable means for actuating said cam to selectively control the position of the movement thereof until said contacts have been separated and means constituted by at least one of said contact elements for continuing the movement of said cam after the disengagement of said transiently engaging means.

3. A slow break switch comprising a plurality of contact elements, means including a cam engaging at least one of said contact elements for moving them apart, a stop member lying in the path of said cam and means including at least one of said contact elements, said cam and said stop member for producing an audible click indicating the operation of the switch.

4. A slow break switch comprising a plurality of contact elements, means mounting said contact elements mutually in wedging pressure engagement, means including a cam for moving at least one of said contact elements slidably away

from the other to open said switch and for controlling the closing thereof, operator means including a transiently engageable connection for actuating said cam and means on at least one of 5 said contact elements for imparting an acceleration to said cam to move it independently of said operator means during a portion of the travel of said contact element.

5. A slow break switch comprising a pair of 10 operating contact members, means mounting said contact members in mutual engagement, means including a cam engaging at least one of said contact members for effecting separation of said contact members, transiently engageable means 15 for actuating said cam to controllably separate said contacts, means including at least one of said contact members and active upon the disengagement of said transiently engageable means for imparting an acceleration to said cam and means

for halting the movement of said cam prior to the normal end of its accelerated movement.

6. A slow break switch comprising a pair of cooperating contact members, means mounting said contact members in mutual pressure engagement, means including a cam bearing upon at least one of said contact members for separating said contact members to open said switch, transiently engageable means for actuating said cam, means including at least one of said contact members for imparting an acceleration to said cam when said transiently engageable means is disengaged, said contact members being positioned to engage with a mutual wiping blow prior to the normal end of said accelerated movement 15 when said cam is actuated to close said switch.

NEWTON C. SCHELLENGER.
